(57) **CLAIM**

The ornamental design for a cable positioning device, as shown and described.

DESCRIPTION

FIG. 1 is a top perspective view of a first embodiment of a cable positioning device;

FIG. 2 is a bottom perspective view of the cable positioning device of FIG. 1;

FIG. 3 is a front view of the cable positioning device of FIG. 1;

FIG. 4 is a back view of the cable positioning device of FIG. 1;

FIG. 5 is a left side view of the cable positioning device of FIG. 1;

FIG. 6 is a right side view of the cable positioning device of FIG. 1;

FIG. 7 is a top view of the cable positioning device of FIG. 1; and

FIG. 8 is a bottom view of the cable positioning device of FIG. 1.

FIG. 9 is a top perspective view of a second embodiment of a cable positioning device;

FIG. 10 is a bottom perspective view of the cable positioning device of FIG. 9;

FIG. 11 is a front view of the cable positioning device of FIG. 9;

FIG. 12 is a back view of the cable positioning device of FIG. 9;

FIG. 13 is a left side view of the cable positioning device of FIG. 9;

FIG. 14 is a right side view of the cable positioning device of FIG. 9;

FIG. 15 is a top view of the cable positioning device of FIG. 9; and,

FIG. 16 is a bottom view of the cable positioning device of FIG. 9.

The cable positioning device can include a hook portion, connected to a vertically extending portion. The hook portion can be in a crimped position, as shown in FIGS. 1-8, or in an open position, as shown in FIGS. 9-16. The vertically extending portion connects to a first substantially rectangular cable saddle. A second substantially rectangular cable saddle is positioned above the first cable saddle, with a U-shaped divider positioned between the first and second cable saddles.

The dash-dash broken lines shown in all of the drawing figures are for illustrative purposes only and form no part of

(Continued)

the claimed design. The dash-dot broken lines represent boundary lines that form no part of the claimed design.
